DRAIN FIXTURE FOR REFRIGERATORS

Migiel J. Uline, Washington, D. C.

Application January 20, 1936, Serial No. 59,974

6 Claims. (Cl. 182—8)

This invention relates to certain new and useful improvements in drain fixtures for refrigerators and more particularly to drain fixtures especially adapted to be connected to the sewerage system whereby the water of the melting ice will be conveyed from the refrigerator to the sewerage system to overcome the difficulties of having to empty receptacles as now employed for collecting the water of the melting ice.

10 Another object of my invention is to provide a drain fixture which can be readily installed in any of the well known makes of refrigerators now in use employing a top ice compartment whereby the difficulty existing of having to empty the ice 15 drippings is overcome and a thoroughly sanitary fixture is provided which can be readily installed or removed to enable it to be disconnected to thoroughly clean the same.

Another object of my invention is to provide 20 a drain fixture with adjustable means for supporting a trap in the proper position in respect to the drain of the ice compartment whereby a liquid seal is formed between the sewerage system and the refrigerator.

25 A still further object of my invention is to provide a drain fixture which is exceedingly simple and cheap in construction and one which can be installed in a refrigerator so as to form an outlet through either the side or back wall of the refrigerator.

30 Other and further objects and advantages of the invention will be hereinafter set forth and the novel features thereof defined by the appended claims.

35 In the drawing,

Figure 1 is a vertical section, partly in elevation, showing the installation of my improved construction of drain fixture;

Figure 2 is a section taken on line 2—2 of Figure 1;

Figure 3 is an enlarged vertical section of a modification showing a slip joint between the trap and elbow; and

Figure 4 is a detail section, partly in elevation, 45 showing the nipple tapped into the outlet of the sink.

In the drawing 1 indicates a refrigerator and 2 the top ice compartment thereof which is provided with the usual drain 3 extending into the cold compartment. This drain is usually connected to a conduit which is provided with a trap and passes out through the bottom of the refrigerator and under which is arranged a receptacle for catching the drippings of the ice. The above 55 description is given so that the operation of my

improved construction of fixture when in use can be clearly understood.

In carrying out my invention I employ a threaded pipe 4 which extends through a suitable opening formed in the wall of the refrigerator and 5 has mounted thereon nuts 5 and packing washers 6 in order to form a tight joint around the opening formed in the wall of the refrigerator and to provide means for adjusting the position of the pipe in the wall and locking it in its ad- 10 justed position.

After the pipe has been forced through the opening formed in the refrigerator, the nuts are 15 screwed up so as to properly position the same and lock it in that position.

The pipe 4 at one end carries an elbow 7 which is threaded onto the pipe and is provided with an internally threaded portion to receive the stem 8 of a liquid trap 9 which is provided with a cup shaped portion 10 into which the stand pipe 11 20 extends which is a continuation of the stem 8 and extends upwardly into the cup shaped portion 10 a sufficient distance to maintain a predetermined level of liquid therein.

Arranged over the stand pipe is a cap 12 which 25 is provided with cut away portions 13 and this forms a liquid seal so as to prevent the odor from passing into the refrigerator.

The top of the cup shaped portion is open and is adapted to be sealed by a rubber washer 14 30 carried by the drain 3 and the upper edge is preferably formed slightly beveled to form a seat for the rubber washer whereby the washer will be resiliently held under tension against this seat in order to completely seal the upper end of the cup 35 of the trap to prevent the odors from the liquid standing therein or from air passing out of the refrigerator.

The opposite end of the pipe 4 carries an elbow 15 which is threaded onto the end of the pipe and 40 has a nipple portion 16 over which is adapted to be slipped a rubber hose 17 to form a conduit for the water, the opposite end of said rubber hose being connected to a nipple 18 of a trap 19 which is provided with a nipple 20 extending into 45 an opening formed in the outlet 21 of the sink 22 which is provided with the conventional liquid trap 23.

The nipple 20 has a substantially semi-circular portion 24 which is adapted to embrace the outlet pipe 21 and is adapted to be clamped in position thereon by flexible bolts 25 extending through apertured ears 26 and provided with nuts 27 for clamping the same, a suitable packing 28 being disposed around the nipple to form a water tight 55

joint as shown, and while I have shown flexible bolts for clamping the same, it is, of course, understood that it can be clamped in various ways without departing from the spirit of my invention.

In the modification shown in Figure 3, the elbow 29 carried by the pipe 4 is provided with a seat 30 to receive the unthreaded stem 31 of a trap 32 in order to allow it to be lifted out of the seat to clean the same, the trap being of sufficient depth so that the distance between the top of the cap and the end of the drain 3 is sufficient to allow the trap to be raised vertically and twisted in order to remove the same.

In the modification shown in Figure 4, I show a nipple 33 tapped into a threaded opening formed in the outlet pipe 21 of the sink and the trap carried thereby is dispensed with and a flexible hose 17 is connected to the nipple 13 and this provides a simple construction whereby an endless conduit can be formed from the trap 9 to the sewerage system above the liquid trap therein.

In installing a drain fixture constructed in accordance with my invention into a refrigerator, a hole is first bored through the wall of the refrigerator and the pipe 4 is slipped through the opening and the nuts and washers placed thereon. The cup shaped trap is then inserted under the drain 3 of the ice compartment and the elbow 30 brought into alignment with the pipe 4 and the pipe is turned so as to screw the same into the elbow, and then by adjusting the position of the pipe, the trap can be properly positioned under the drain and by tightening the nuts on the pipe, it will be locked in this position. The elbow 15 is then applied to the outer end of the pipe and the nipple, which is connected to the sewerage system, is connected to the nipple of the elbow by a rubber hose so as to complete a trap tight conduit between the sewerage system and the drainage system of the refrigerator.

When it is desired to remove the trap 9 as shown in the preferred embodiment of my invention to clean the same, it is only necessary to unscrew the same from the elbow 1 and raise the same out of the elbow, the flexible washer allowing the trap to be raised and turned.

By removing the hose 17 from the elbow 15, hot water can be poured down the hose 17 to flush the system.

If desired, the clamping means for the nipple 20 can be released in order to allow the same to be detached.

In the form shown in Figure 3, it is only necessary to lift the stem 31 in the trap out of the elbow in order to remove the same for cleaning.

In the form shown in Figure 4, the trap is dispensed with and a very simple construction of drain system is provided for a refrigerator.

While in the preferred embodiment of my invention I have shown a trap disposed adjacent the outlet pipe of the sink, I wish it to be clearly understood that this trap can be dispensed with and a nipple substituted therefor or that the trap 9 can be dispensed with and a connection formed between the elbow 1 and the outlet pipe 3 of the ice box without departing from the spirit of my invention.

From the foregoing description it will be seen that I have provided a drain fixture for a refrigerator comprising an adjustable member mounted within the wall of a refrigerator to allow it to be aligned with the outlet of the ice compartment of the ice box and by having a conduit 75 connected to the outlet of the drain above a liquid

trap, a suitable trap being disposed in the drain fixture either at the point of connection with the outlet of the sink or the outlet of the ice compartment or both whereby I am able to take care of the drainage of the refrigerator so as to overcome the difficulties existing.

It will be apparent that the top ice compartment of a refrigerator is elevated a sufficient distance to allow a free flow by gravity of water melting from the ice to the point of connection 10 of the sewerage system.

What I claim is:

1. A drain fixture for refrigerators having a top ice compartment having a drain leading therefrom comprising an externally threaded pipe extending through the wall of the refrigerator, members threaded on said pipe at each end for adjustably securing said pipe in position therein in respect to said drain, a liquid trap supported by said pipe and disposed adjacent said ice compartment under the drain leading therefrom and a flexible conduit leading from the other end of said pipe having a connection with the sewerage system above the liquid trap disposed therein.

2. A drain fixture for refrigerators having a top ice compartment provided with a drain leading therefrom comprising an externally threaded pipe extending through the wall of the refrigerator, members threaded on said pipe at each end for adjustably securing said pipe in position therein in respect to said drain, an elbow carried by one end of said pipe, a liquid trap supported by said elbow and disposed adjacent said ice compartment under the drain leading therefrom, said trap having an open top to receive the drain, a flexible washer carried by said drain pipe for sealing said trap, a flexible conduit leading from the other end of said pipe and a trap tapped into the sewerage system having a nipple to which the free end of said conduit is connected.

3. A drain fixture for refrigerators having a top ice compartment having a drain leading therefrom comprising an externally threaded pipe extending through the wall of the refrigerator, members provided on said pipe at each end for adjustably securing said pipe in position therein in respect to said drain, a liquid trap supported by said pipe and disposed adjacent said ice compartment, a flexible conduit leading from the other end of said pipe, a nipple having a connection with said conduit, said nipple being disposed within an opening formed in the outlet of a sink and means for clamping said nipple to said outlet.

4. A drain fixture for refrigerators having a top ice compartment provided with a drain leading therefrom comprising an externally threaded pipe extending through the wall of the refrigerator, members threaded on said pipe at each end for adjustably securing said pipe in position therein in respect to said drain, an elbow carried by one end of said pipe, a liquid trap detachably supported by said elbow and disposed adjacent said ice compartment under the drain leading therefrom, said trap having an open top to receive the drain, a flexible washer carried by said drain pipe for sealing said trap, a flexible conduit leading from the other end of said pipe, a trap connected to the sewerage system having a nipple to which the free end of said conduit is connected and means for clamping said trap to the outlet of said sink.

5. A drain fixture for refrigerators having a top ice compartment having a drain leading therefrom comprising a pipe extending through the

wall of the refrigerator, members movably mounted on said pipe for adjustably securing said pipe in position therein in respect to said drain, a liquid trap adjustably supported by said pipe under said drain, a flexible conduit leading from the other end of said pipe and means for connecting said flexible conduit to the sewerage system.

5. A drain fixture for refrigerators comprising an adjustable member adapted to be adjustably

mounted within the wall of the refrigerator under the ice compartment and adapted to form a conduit for the water melting from the ice, a trap detachably carried by said member and adapted to be disposed under the drain of the ice box, a flexible conduit leading from the outer end of said adjustable member and means for connecting said conduit to the sewerage system.
